UNITED STATES PATENT OFFICE.

JOHN B. BASKERVILLE, OF ROANOKE, VIRGINIA, ASSIGNOR TO IMPACTOGRAPH CORPORATION, OF ROANOKE, VIRGINIA, A CORPORATION OF VIRGINIA.

RECORDING MECHANISM.

Application filed May 29, 1925. Serial No. 33,629.

This invention relates to improvements in recording mechanisms.

An object of the invention is to provide a mechanism adapted for recording sudden accelerations and decelerations in the movements of vehicles, and more particularly railroad cars.

Another object of the invention is to provide a recording mechanism of this character, including a pendulous or swinging member, which is adapted to be operatively displaced by sudden differences in the movements of the vehicle, in conjunction with a record sheet, and a stylus associated with said swingable member for marking the record sheet, together with means automatically operable by the movement of the swingable member for changing the position of the stylus with reference to the record sheet so as to record thereon at different positions on the sheet, successive shocks imparted to the railway car.

A further object of the invention is to provide key means for releasing the stylus after the same has moved sufficiently to complete a record of one trip or run of the vehicle, or other specified time, in order to prepare the mechanism for making a new record, said mechanism prior to the manipulation of the key means being protected against tampering, which may be detected by an examination of the sealing means associated with the mechanism.

Another object of the invention is to provide means for maintaining the swingable member in a central position with reference to the housing in which it is mounted, and to provide means for securing the housing to the car structure, said means being adapted to automatically disconnect the holding means for the swingable member, when said means are operated to secure the mechanism to the car structure.

Other and further objects of the invention will more fully and clearly appear from the description and claims hereinafter following.

In the drawings, forming a part of this specification, Figure 1 is a longitudinal, vertical, sectional view, through my improved mechanism. Figure 2 is a transverse sectional view on the line 2—2 of Figure 1. Figure 3 is a transverse sectional view of the invention similar to Figure 2 upon an enlarged scale showing parts of the operating mechanism in section. Figure 4 is a horizontal, sectional view through the swingable member asso-

ciated with the device on the line 4—4 of Figure 1. Figure 5 is a vertical, sectional view of the marking mechanism on the line 5—5 of Figure 4. Figure 6 is a broken elevational view of the key by which the stylus mechanism may be manipulated. Figure 7 is a fragmentary, enlarged, elevational view of a different embodiment of the actuating means for determining the position of the stylus. Fig. 8 is a detail, fragmentary, transverse sectional view, taken through the bottom of the housing and showing to advantage the screw bolts and their manner of connection with the housing and pendulum.

The invention broadly comprises a housing A, a record sheet and means for maintaining the same in position, indicated at B, the movable means sensitive to shocks imparted thereto and indicated at C, the stylus mechanism D associated with said movable means, actuating means E co-operating with the stylus to change its position relative to the movable member, means for releasing the stylus upon completion of the record indicated at F, means for retaining the movable member in a central position, when the device is not in use indicated at G, and means H for securing the mechanism to the car walls, said means co-operating with the retaining means for the movable member to automatically release the same when they are operating to secure the mechanism to the car structure.

The housing A is of substantially box-like form, within which the recording mechanism proper is disposed. The housing A comprises a body portion 10, and a removable lid 11 for closing the same. The bottom wall 12 of the housing is preferably disposed inwardly of flanges 13, and secured to such flanges in any suitable manner.

The record sheet B is arranged to be disposed upon the inner surface of the front wall 14 of the housing, brackets 16 being secured to the inner side of the wall 14, adjacent the ends and bottom thereof, with which the edges of the sheet B are engaged and by which it is held in position, the horizontally extending slot 15 being formed in the wall 14 for the insertion and removal of the recording sheet. The front wall 14 is provided with a plurality of pins 18 upon which is removably disposed a plate 17 which covers the slot 15, said plate being secured in position by sealing members 19 which extend through the pins 18, the arrangement being 110

such that the seals have to be broken to gain access to the recording sheet, and thus unauthorized tampering may be immediately detected.

6 The movable means C comprise a pendulous member swingably mounted upon the shaft 20 extending transversely of the mechanism, said shaft having its ends journaled in journal bearings 21 secured to the 10 front and rear walls of the housing at a central position between the ends thereof, and adjacent the top edges of the same. The member C is provided with a hub 22 through which the shaft 20 extends, the body portion 15 of the member C depending centrally from the hub portion 22 as indicated at 23, the portion 23 being weighted at its bottom as indicated at 24 to insure uniform movement of the pendulum. The member C is provided with 20 an elongated rectangular slot 25 intermediate its ends, providing side portions 26 and 27, which on their rear inner surfaces are rabbeted as indicated at 28, and 29, a rack 30 being fixedly mounted in the rabbet 28, and 25 the rabbet 29 providing a runway for a movable ratchet 31, said movable ratchet being arranged to co-operate with the actuating mechanism E hereinafter more fully described.

30 Mounted for sliding movement between the members 26 and 27 is the stylus D. The stylus proper is indicated at 32, and forms part of a body 33, which has shoulders 34 at its forward portion, and is provided with 35 wings 35 at its rear portion, said wings being adapted to bear against the adjacent extensions 36 formed upon the mounting block 37, said mounting block engaging the inner surfaces of the members 26 and 27 and having the 40 outer ends of the same connected to a plate 38 which slides upon the front faces of the members 26 and 27, and through which the stylus proper slidably extends, the shoulders 34 of the stylus body portion 33 bearing 45 against the flanges 39 formed upon the member 37. The block 37 has secured thereto a spring 40 which extends over the body portion of the member 33 and normally urges the stylus forwardly. The block 37 also is 50 provided with a spring 41 which bears against one of the wings 35 on the body member 33 and against the stationary rack 28, and is adapted to engage the teeth of said rack to support the mechanism D in a definite position 55 with respect to the pendulum C. The opposite side portion of the block 37 is also provided with a spring 42, extending over the other wing 35 of the stylus body and is inturned and adapted to engage the teeth 60 of the movable ratchet 31.

The actuating means E for moving the rack 31 comprises a spring 43 which normally presses the ratchet 31 downwardly, the ratchet 31 having a portion 43' projecting beyond the end of the pendulum C, in

such position as to co-operate with cam means 44, said means being provided with an offset portion 45, which is normally spaced from the end 43' of the rack member 31 when the same is in its outermost position, the extent of the offset portion 45 being such as to permit swinging of the pendulum C through a certain arc, which permits movements of the pendulum without actuation of the recording mechanism, thus allowing for the ordinary shocks imparted to the car without recording the same. At each side of the offset portion 45 of the member 44, the portions 45^a of the member 44 project into and follow the path of the end 43' on the rack 31, so that when the pendulum C swings beyond the offset portion under unusual shock, the rack 31 is forced upwardly, moving the stylus mechanism upwardly, and when the pendulum returns to central position, the movable rack 31 is free to return to initial position, moving past the stylus mechanism which is held against return movement by engagement of the spring 41 with the stationary ratchet 28.

An adjusting spring 46 is provided for regulating the movements of the pendulum C, said spring being connected to an extension 47 on the hub 22, and being adjustably connected to the pin 48 threaded in a bracket 49, the lower end of the pin having a nut 50 threaded thereon.

When the stylus mechanism D has traveled the desired distance along the pendulum, in order to make a new record, the same will have to be removed to the lower portion of the pendulum, and this is accomplished by means of the insertion through suitable openings 50^a in the housing, the pendulum, and the block 37, of the key 51^a, the body portion of the stylus being provided with an enlarged key slot 52^a for the reception of the head of the key, turning movement of the key serving to move the stylus body 33 rearwardly against the pressure of the spring 40, thereby moving the wings 35 of the body portion outwardly which disconnects the springs 41 and 42 from the racks 28 and 29, permitting movement of the stylus mechanism to a lower position with reference to the pendulum C.

The retaining means G comprise angular members 51, which are provided with turned ends 52 normally engaging recesses 53 in the pendulum bob 24, such members being provided with cranks 54 by which they may be disconnected, the members being disposed within the casing, and of course not being accessible from the exterior thereof.

The means H for securing the housing A in the car structure, comprise screw bolts 55, and 56, the screw bolts 55 extending through the lower end of the casing, and through the angular members 54 of the retainers 51, each pin being provided with a member 56^a which is movably connected to the related angular

- member 54, the construction being such that when the screw bolts 55 are screwed into the car wall, movement of such screws serves to swing the retainers 51 out of engagement with the pendulum during the securing operation. The screws 56 extend through the flanges of the lid 11 such screws when they are fastened to the car structure serving to hold the lid in position upon the casing.
10. When it is desired to use the mechanism to record shocks imparted to the car structure, a fresh record sheet B is placed in the guides 16 through the slot 15, and the plate 18 secured in position over the slot, the stylus mechanism D being arranged adjacent the lower end of the pendulum C. When the housing A is secured to the car structure by the screw bolts 55, the retainers 51 are released to permit swinging movement of the pendulum C, it being noted also that the screw bolts 56 hold the cover upon the housing, so that the mechanism therein is entirely inaccessible. During the usual and ordinary buff and draft shocks imparted to the car, the pendulum will swing only a limited distance, not sufficient to cause the same to move past the offset portion 45 in the cam means 44; however upon unusual shocks being imparted to the car, such as will swing the pendulum C beyond the offset portion 45, the engaging end 43 of the movable rack will come in contact with the portions of the members 44 beyond the offset portion, and be elevated thereby, such elevation being transmitted to the block 37, carrying the stylus mechanism with the rack, and causing the stylus of course to record the impact upon the sheet B, the length of the arc recorded of course determining the intensity of the impact. When the pendulum returns to central position, as soon as the same is in line with the offset portion 45, the movable rack will be urged to initial position by the spring 43, the spring 42 of the stylus block sliding over the ratchet teeth.
45. However the spring 41 which is in engagement with the teeth of the stationary rack 28 will prevent the return of the stylus block 37, and consequently the stylus mechanism will have been advanced or elevated a certain extent, successive unusual swinging movements of the pendulum causing a step by step movement of the stylus means along the pendulum C thus providing means for marking the record sheet B at different positions for each unusual shock. When the record is completed, as at the end of the run or at the end of a certain period of time, the record sheet B may be withdrawn from the housing through the slot 15, and another record sheet inserted in place thereof. In order to move the stylus means toward the bottom of the pendulum means, the key 51^a is inserted into the housing and engages the body member 33 carrying the stylus 32, such stylus being retracted upon rotation of the key,

thereby disconnecting the springs 41 and 42 from the ratchet members 30 and 31, permitting the stylus mechanism to be moved in position to make a new record.

A slightly different embodiment of the invention is illustrated in Figure 7, all of the parts except the means for actuating the movable rack being identically similar to those heretofore referred to, and consequently the same will be designated by the same reference characters. In this construction the cam means 44 is entirely eliminated, and such cam means placed upon the shaft 100 which supports the pendulum, the stationary cam member 101 being provided with an offset portion 102 with which the end portion 103 of the movable rack 31 engages, a spring 104 being provided similar to the spring 43, except that the same urges the rack member upwardly instead of downwardly, the operation being such that upon excessive swinging movement of the pendulum C, the movable ratchet 31 is depressed, sliding over the spring 36, but upon the return of said member 31 under the influence of the spring 104, the stylus means D are elevated as heretofore referred to, and held in an elevated position by means of the spring 41, successive movements of the rack 31 causing successive movements of the stylus means D to new positions so as to obtain a separate marking upon the sheet of each unusual shock imparted to the mechanism, as before explained.

While I have herein shown and described what I now consider the preferred manner of carrying out my invention, the same is merely illustrative and I contemplate all changes and modifications that come within the scope of the claims appended hereto.

I claim:

1. In a device of the character described, the combination with a record sheet; of a swingable member sensitive to shock; means carried by said swingable member for marking said sheet; and means for automatically changing the position of said marking means with reference to said swingable member. 105
2. In a device of the character described, the combination with a record sheet; of a swingable member sensitive to shock; means carried by said swingable member for marking said sheet; and means for automatically changing the position of said marking means with reference to said swingable member, said automatic means being arranged to successively advance said marking means relative to said swingable member and said sheet to separately record a plurality of shocks. 115
3. In a device of the character described, the combination with recording means; of a member sensitive to shock and movable relative to said recording means; marking means associated with said movable member and co-operating with said recording means; and means for changing the position of said 125
- 65

marking means to obtain a separate record of a plurality of shocks, said means including a member movable with reference to said movable means and arranged to advance said marking means when moving in one direction and to be freed of said marking means when moving in the opposite direction, and means for retaining said marking means in the position assumed when displaced by said movable means.

4. In a mechanism of the character described, the combination with a record sheet; of a member movable relative to said record sheet; marking means co-operating with said movable member and said record sheet; means arranged to advance said marking means with reference to said movable member in one direction, said marking means being retained in advanced position upon return of said advancing means in the opposite direction; and cam means for actuating said advancing means.

5. In a device of the character described, the combination with recording means; of a swingable member; marking means carried by said swingable member and co-operating with said recording means; means for advancing said marking means relative to said swingable member upon movement in one direction; means for retaining said marking means in advanced position upon the return of said advancing means; and cam means regulated by movement of said swingable member for actuating said advancing means.

6. In a recording mechanism, the combination with a record sheet; a movable member; marking means carried by said movable member and co-operating with said sheet to mark the same; a stationary rack associated with said movable member; a movable rack associated with said member; means for actuating said movable rack; and means associated with said marking means adapted to engage said movable rack and to be advanced thereby, said means including elements co-operating with said stationary rack to hold the marking means in advanced position upon return of said movable rack.

7. In a recording mechanism, the combination with a record sheet; a movable member; marking means carried by said movable member and co-operating with said sheet to mark the same; a stationary rack associated with said movable member; a movable rack associated with said member; means for actuating said movable rack; means associated with said marking means adapted to engage said movable rack and to be advanced thereby, said means including elements co-operating with said stationary rack to hold the marking means in advanced position upon return of said movable rack; means normally urging said movable rack in one direction; and cam means operable upon

movement of said movable member to advance said movable rack.

8. In a device of the character described, the combination with a record sheet; a swingable member; marking means carried by a swingable member and co-operating with said sheet to mark the same; means movable relatively to said swingable member; means conforming to the arc of swinging movement of said member and being arranged in one position to move said movable member relatively to said swingable member; and means associated with said marking means adapted to be advanced by the movement of said movable member.

9. In a device of the character described, the combination with a record sheet; a swingable member; marking means carried by a swingable member and co-operating with said sheet to mark the same; means movable relatively to said swingable member; means conforming to the arc of swing of said swingable member and being arranged to impart successive movements to said movable member; means associated with said marking means to be progressively advanced by said movable member.

10. A device of the character described, including a swingable member; means longitudinally movable relative to said swingable member; an element longitudinally movable with reference to said swingable member and co-operating with said longitudinally movable means to advance the same when said element is moved in one direction and to move past said means in an opposite direction; means for imparting successive reciprocations to said element; and means for retaining said longitudinally movable means in its advanced position after each reciprocation.

11. In a device of the character described, the combination with a record sheet; of a swingable member movable with reference to said record sheet; marking means comprising an element longitudinally movable with reference to said swingable member, and including a stylus, said marking means being provided with spring means; a stationary rack on said swingable member adapted to be engaged by said spring means, and a movable rack adapted to be engaged by said spring means, said stylus being normally urged to operative position by said spring means; and means for imparting reciprocation to said movable rack.

12. In a device of the character described, comprising a record sheet; a member swingable with reference to said record sheet; marking means associated with said swingable member; means for retaining said swingable member in a central position when said mechanism is not in use; and means for securing said mechanism in operative position, said retaining means being arranged so that connection of said securing means serves to

disconnect said retaining means to permit swinging movement of said swingable member.

13. A recording mechanism including a housing equipped with marking means swingable in response to shocks, a record sheet fixedly carried by the housing in the path of movement of the marker, and means for auto-

matically feeding the marker along the sheet during swinging movement of the marking means. 10

In witness that I claim the foregoing I have hereunto subscribed my name this 21st day of May, 1925.

JOHN B. BASKERVILLE.
